FILLER FOR PULP REFINING ENGINES

Charles J. Steinbarger, Dayton, Ohio, assignor to
Simonds Worden White Company, Dayton,
Ohio, a corporation of Ohio

Application August 8, 1939, Serial No. 289,001

11 Claims. (Cl. 92—27)

This invention relates to Jordan engines or similar pulp producing apparatus. The ordinary Jordan comprises a frusto-conical outer member or shell, which is usually stationary, and a frusto-conical inner member or plug, which is rotatable in the shell. The shell and plug are provided with opposed working surfaces between which is passed the material to be reduced, commonly called "stuff." It is customary to provide the working surfaces on structures, herein called fillers, which are separate from but are attached to the shell and plug respectively. Such a filler usually comprises a series of metallic reducing members or blades arranged on edge and connected one with the other laterally spaced relation. The spaces between the reducing members are ordinarily filled with plastic material to a level adjacent the working edges of the reducing members, the distance which the reducing members project beyond the hardened plastic material being determined, in part at least, by the character of the work to be done. The quality of the finished product depends largely upon the character and arrangement of the reducing members.

One object of the invention is to provide a filler of simple construction in which the reducing members may be produced at low cost and easily assembled.

To this end it is a further object of the invention to so construct and arrange the reducing members that they may be connected one with the other by the insertion of connecting members extending lengthwise of the filler.

A further object of the invention is to so form and arrange the reducing members that they will have a highly efficient action on the stuff and will produce a finished stuff of fine quality.

A further object of the invention is to provide a filler which will not only enable the Jordan to produce a product of superior quality but will impart thereto a relatively high capacity.

Other objects of the invention may appear as the device is described in detail.

In the accompanying drawing Fig. 1 is a longitudinal section taken through the shell and plug of a Jordan with the fillers applied thereto; Fig. 2 is a plan view of a portion of a filler embodying the present invention; Fig. 3 is a detail section taken on the line 3—3 of Fig. 2; Fig. 4 is a perspective view of one of the blades of the reducing member shown in Fig. 2; and Fig. 5 is a plan view of a portion of a filler of modified form.

In this drawing there are shown two embodiments of the invention but it will be understood that these have been chosen for the pur-

pose of illustration only and that the filler may be used with apparatus of various kinds and may take various forms without departing from the spirit of the invention.

In both of the illustrated embodiments the filler comprises a plurality of reducing members extending lengthwise of the filler, spaced laterally one from the other and so shaped as to provide a tortuous passageway between adjacent reducing members. Each reducing member comprises a longitudinal series of inclined parts, adjacent parts being inclined in opposite directions so as to provide the reducing member with recesses facing alternately in opposite directions, the recesses in the adjacent faces of contiguous reducing members being connected one with the other to form a tortuous passageway for the stuff. Each reducing member is provided with openings to receive a longitudinal connecting member, openings in adjacent reducing members being so arranged that a single connecting member will pass through openings in both reducing members, thus connecting the two reducing members one to the other. Preferably the connecting member is in the form of a round rod so as to permit the reducing members to move about longitudinal axes and thus conform to the shape of the Jordan element to which they are to be applied, that is, to the shell or the plug as the case may be.

In that embodiment shown in Figs. 1 to 4 the reducing members are indicated as a whole by the reference numeral 10 and each reducing member comprises a bar which extends for the full length of the filler, it being understood that a single filler may extend for the full length of the Jordan or that it may be formed in a series of sections, the combined length of which is equal to that of the shell and plug. The reducing bar as a whole is made up of a series of relatively short bars or blades arranged on edge and extending at an inclination to the length of the reducing bars, the adjacent blades or short bars being inclined in opposite directions to provide the reducing bar with recesses 12 facing the opposite sides of that bar. Each inclined blade 11 is provided adjacent both edges thereof with openings 13 adapted to receive a connecting rod 14. Preferably each blade has at each side thereof an edge portion 15 which extends at substantially right angles to the length of the reducing bar so that the lateral edge portions of adjacent bars may abut one against the other and the openings 13 are formed in these lateral portions. Preferably the lateral edge por-

tions 15 of each blade extend for the full height, or length, of the blade, so that the outer or working edge of the blade, which is the top edge of Fig. 2, will extend for the full width of the blade but obviously if desired the outer portions of the lateral edges of the blade may be cut away to shorten the working edge thereof. The corresponding inclined blades of each of the several reducing bars or members are arranged in series circumferentially of the filler, so that the abutting edge portions of the oppositely inclined blades of each reducing member will extend into the recess 12 of an adjacent reducing bar and the openings therein will be arranged in substantial alignment with the openings in the adjacent edges of the blades of said adjacent reducing bar. Thus the connecting bars 14 serve both to connect the blades of the individual reducing bars one with the other and, to connect the adjacent reducing bars one with the other, and this arrangement also provides for communication between the recesses in adjacent bars so as to form a tortuous passageway through which the stuff travels. The longitudinally extending connecting rods 14 are inserted lengthwise through the aligned openings as the several parts of the filler are assembled thus enabling the same to be assembled rapidly, either on that element of the Jordan to which the filler is to be applied or separately therefrom, and when round rods are used the adjacent reducing bars are pivotally connected so that they may accommodate themselves to the contour of the element of the Jordan to which the filler is to be applied.

It will be noted that the individual bars or blades of each reducing bar decrease gradually in length from one end of the filler to the other so as to impart to the filler a frusto-conical shape corresponding to the shape of the shell or plug, as the case may be. When the several parts of the filler have been assembled the spaces between adjacent reducing bars are filled to a level adjacent the working edges thereof with plastic material which, when hardened, forms the bottom of the passageway over which the stuff travels and, if desired, the plastic material may be of such a character that when hardened it will have an abrasive surface which will have a reducing action on the stuff as the latter moves over the surface. This arrangement is illustrated in Fig. 1 where the shell is shown at 18, the plug at 19, and the plastic material at 20. The connecting rods being inserted in the inner parts of the blades or inclined portions of the reducing bar, are embedded in this hardened plastic material and thus the connecting rods and the blades are held firmly against movement. Therefore it is not essential that the connecting bars be provided with fastening devices to retain them in position but, if desired, fastening devices of any suitable character may be provided and, as shown in Fig. 2, the ends of the connecting bars are upset, after the manner of a rivet, on the outer sides of the end blades of each reducing member, as shown at 16. If desired spacing sleeves 14a may be placed on the rods 14 between adjacent parts of the blades, but ordinarily this is not necessary. When the working edges of the several blades extend for the full width of the blades it will be apparent that these working edges extend beyond the connecting rods and into the recesses of adjacent reducing members. The lateral edge portions of the blades may be of such width that the blades will extend into the recesses any desired distances but preferably they

extend only relatively short distances into the recesses so that they are spaced a substantial distance from the closed ends of the recesses, thus causing a turbulence of the stuff as it flows through the recesses, which will cause different portions of the stuff to flow over the working edges of the successive blades and thus be subjected to the action of the reducing members on both the shell and the plug.

In Fig. 5 there is illustrated a modified form of the filler in which each reducing member comprises a single bar 21 which extends for the full length of the filler and is bent or otherwise formed to impart thereto a zigzag shape in which relatively short portions 22 of the bar are inclined laterally and adjacent portions are inclined in opposite directions, so as to provide each bar with recesses 23 facing alternately in opposite directions. The several reducing bars are arranged in substantially parallel relation one to the other so that the converging portions of each bar extend into a recess of an adjacent bar, each bar being spaced one from the other to form between adjacent bars tortuous passageways or channels. At least a part of the inclined portions of each bar are provided with openings to receive connecting bars 24, there being two such openings in each of said inclined portions and the openings being so arranged that each of the openings in each inclined portion of each bar will be in line with an opening in the inclined portion of another bar, thus permitting the connecting rods to be inserted for the purpose of retaining the several bars in proper relation one to the other. When each reducing member comprises a single bar it is not essential that the connecting rods extend for the full length of the filler but, as shown in Fig. 5, it is only necessary that each rod should extend through two or more of the inclined portions of adjacent bars. The spaces between adjacent bars are filled with plastic material to a level adjacent the working edges thereof and the connecting rods are so arranged that they will be embedded in that plastic material and therefore it is not necessary to provide fastening devices to retain the connecting rods in position.

In both embodiments of the invention the reducing members are of such a character that they can be quickly and easily formed at small expense and can be easily assembled by the mere insertion of the longitudinal connecting rods through the openings in the bars, thus enabling the filler to be produced at a relatively low cost. Further, the arrangement of the reducing members is such as to control and retard the flow of the stuff through the Jordan in such a manner as to provide a very effective reducing action on the stuff.

While I have shown and described two embodiments of my invention I wish it to be understood that I do not desire to be limited to the details thereof as various modifications may occur to a person skilled in the art.

Having now fully described my invention, what I claim as new and desire to secure by Letters Patent, is:

1. In a filler for a pulp refining engine, a plurality of stuff reducing members extending lengthwise of said filler and spaced laterally one from the other, each reducing member having adjacent longitudinal portions inclined laterally in opposite directions and arranged to form tortuous passageways between adjacent members, and connecting members extending lengthwise

of said filler and attached to the adjacent reducing members to connect the latter one to the other.

2. In a filler for a pulp refining engine, a plurality of stuff reducing members extending lengthwise of said filler and spaced laterally one from the other, each reducing member having a plurality of laterally converging portions arranged to provide lateral recesses in said member, the converging portions of each member extending into the corresponding recesses of an adjacent member, said adjacent members having longitudinally aligned openings, and connecting members extending through said aligned openings to connect said reducing members one with the other.

3. In a filler for a pulp refining engine, a plurality of reducing members extending lengthwise of the filler, spaced laterally one from the other 20 and shaped to provide a tortuous longitudinal passageway between adjacent members, each member having near each side thereof a longitudinal series of openings, the openings in the contiguous sides of adjacent members being in substantial alinement, and connecting members 25 extending lengthwise of the filler through the openings in said adjacent members.

4. In a filler for a pulp refining engine, a plurality of stuff reducing members extending 30 lengthwise of said filler and spaced laterally one from the other, each reducing member having a plurality of parts extending transversely to the length thereof and arranged to provide said member with recesses facing alternately in opposite directions, each transverse part having 35 openings near the respective sides of said member, and connecting members extending lengthwise of said filler and mounted in the corresponding openings in adjacent reducing members to connect said adjacent members one with 40 the other.

5. In a filler for a pulp refining engine, a plurality of stuff reducing members extending lengthwise of said filler and spaced laterally one 45 from the other, each reducing member having a plurality of parts extending transversely to the length thereof and arranged to provide said member with recesses facing alternately in opposite directions, and connecting members extending lengthwise of said filler, each connecting member being attached to the transversely extending parts on the contiguous sides of adjacent reducing members.

6. In a filler for a pulp refining engine, a plurality of stuff reducing members extending lengthwise of said filler and spaced laterally one from the other, each reducing member comprising a longitudinal series of separate elements extending obliquely to the length thereof, adjacent 55 elements being inclined in opposite directions, and means for connecting the elements of each reducing member one with the other and for connecting adjacent reducing members one with the other.

7. In a filler for a pulp refining engine, a plurality of stuff reducing members extending lengthwise of said filler and spaced laterally one from the other, each reducing member comprising a longitudinal series of separate elements 5 extending obliquely to the length thereof, adjacent elements being inclined in opposite directions, and connecting members extending lengthwise of said filler, said connecting members and said elements having parts cooperating to connect the elements of each reducing member one with the other and with the elements of the adjacent reducing members.

8. In a filler for a pulp refining engine, a plurality of stuff reducing members extending 15 lengthwise of said filler and spaced laterally one from the other, each reducing member comprising a longitudinal series of separate elements extending obliquely to the length thereof, adjacent 20 elements being inclined in opposite directions, and each element having openings adjacent the respective sides of said reducing member, and longitudinal connecting members extending through openings in the elements of adjacent reducing members.

9. In a filler for a pulp refining engine, a plurality of stuff reducing members extending lengthwise of said filler and spaced laterally one from the other, each reducing member comprising a longitudinal series of separate elements, 30 each element extending obliquely to the length of said reducing member and having lateral edge portions extending at substantially right angles to the length of said member and provided with openings, adjacent elements being inclined in 35 opposite directions, and connecting rods extending lengthwise of said filler through the openings in the elements of adjacent reducing members.

10. In a filler for a pulp refining engine, a plurality of stuff reducing members extending lengthwise of said filler and spaced laterally one from the other, each reducing member comprising a single bar bent to provide the same with a series of laterally inclined portions, at least a 45 part of said inclined portions having openings, and connecting rods extending lengthwise of said filler through the openings in adjacent reducing members.

11. In a filler for a pulp refining engine, a plurality of stuff reducing members extending lengthwise of said filler and spaced laterally one from the other, each reducing member comprising a single bar bent to provide the same with a series of laterally inclined portions, inclined 55 portions of each bar having openings in longitudinal alinement with the openings in inclined portions of at least two other bars, connecting rods extending through said aligned openings, and hard material arranged in the spaces between 60 said bars to form the inner walls of the passageways between said bars.

CHARLES J. STEINBARGER.
